(57) **CLAIM**

The ornamental design for a power box for a lighting system, as shown and described.

DESCRIPTION

FIG. 1 is a front perspective view of the power box for a lighting system showing my new design;

FIG. 2 is a top plan view thereof;

FIG. 3 is a rear elevational view thereof;

FIG. 4 is a right side elevational view thereof;

FIG. 5 is a left side elevational view thereof; and,

FIG. 6 is a bottom plan view thereof.

The broken lines in the drawings are included for the purpose of illustrating portions of the article that form no part of the claimed design.
